INCINERATOR

Filed Dec. 9, 1922

2 Sheets-Sheet 2

UNITED STATES PATENT OFFICE.

JOHN W. STOKES, OF DALLAS, TEXAS.

INCINERATOR.

Application filed December 9, 1922. Serial No. 605,602.

To all whom it may concern:

Be it known that I, JOHN W. STOKES, citizen of the United States, residing at Dallas, in the county of Dallas and State 5 of Texas, have invented certain new and useful Improvements in Incinerators, of which the following is a specification.

This invention relates to new and useful improvements in incinerators.

10 The object of the invention is to provide certain improvements upon my furnace for which Letters Patent were granted May 9th, 1916, No. 1,182,511.

A particular object of the invention is to 15 provide an auxiliary combustion chamber separated from the main combustion chamber, but interposed between the said main chamber and the stack, whereby a more complete combustion and ignition of the gases 20 is had, which results in a substantial elimination of the odorous gases.

A construction designed to carry out the invention together with other features of the invention will be hereinafter described.

25 The invention will be more readily understood from a reading of the following specification and by reference to the accompanying drawings in which an example of the invention is shown and wherein:

30 Fig. 1 is a front elevation of an incinerator constructed in accordance with my invention,

Fig. 2 is a horizontal cross-sectional view taken on the line 2—2 of Fig. 1,

35 Fig. 3 is a longitudinal sectional view taken on the line 3—3 of Fig. 2, and

Fig. 4 is a transverse sectional view on the line 4—4 of Fig. 2.

In the drawings the numeral 10 designates 40 a base or bottom from which a front wall 11 and a back wall 12 extend upwardly and are connected by side walls 13 and 14 respectively, also projecting upwardly from the base. The side walls are connected by

45 an arch 15 of refractory material which extends from the front wall to the rear wall and forms the roof of the combustion chamber enclosed by the base 10 and the walls 11, 12, 13 and 14. The entire chamber is preferably lined with refractory material such as fire bricks. Over the arch a platform 16 is constructed in accordance with the practice in this art. An opening 17 is provided 50 in the top of the furnace and is closed by a cover 18. By removing the cover garbage,

carcasses and other waste matter either wet or dry may be dumped into the incinerator.

The rear wall 12 is curved downwardly and forwardly at its intersection with the base and merges into the floor of the furnace, which is provided with a sump 19 adjacent said curved portion for the reception of oils and liquids. At the front central portion of the base an ash grate 20 is disposed over a pit 21, access to which is had by doors 22. The matter which is dumped into the combustion chamber falls upon the floor or base 10 and the rear portion of the grate 20 and the incinerated portions may be raked forwardly at intervals 65 so that the ashes will fall thru the grate into the pit 21. The unconsumed matter may be raked onto the grate and the draft may be accelerated by opening the lower door 22.

Adjacent the side wall 13 a fuel grate 23 70 is arranged and extends rearwardly from a fire opening 24 in the front wall. An extension grate 25 in the form of a continuation of the grate 23 is also provided. The grates are over a pit 26 which is closed at 75 its front end by a door 27. On the side grate 23 opposite from the wall 13, a baffle wall 28 extends rearwardly from the front wall 12 and from the base to the arch. The firebox which is thus formed over the grate 23 and the grate 25 is closed at its front end 80 by a door 29. The rear portion of the grate 25 extends beyond the baffle wall.

Along the opposite side of the main combustion chamber and contiguous to the wall 90 14, auxiliary grates 30 are arranged in adjacent relation to the grate 20. Access is had to these grates 30 thru an opening 31 in the front wall and a pit 32 is provided under said grates. A door 33 closes the opening 95 31, while a door 34 closes the front end of the pit. The matter dumped into the main combustion chamber falls and is also raked onto the grates 30.

At the spring of the arch 15 a horizontal 100 duct 35 provides an escape for the gases into an auxiliary combustion chamber 36 disposed parallel with the main chamber. The duct is elevated above all the grates and creates an efficient draft. At the rear end 105 of the auxiliary chamber 36 is erected an outside smoke stack 37, which has communication with the chamber 36 by a duct 38. Access may be had to the stack thru a clean-out door 39 disposed below the duct 38.

In operating the incinerator a fire is first built upon the grate 23, fuel being introduced thru the opening 24. A considerable draft will be produced by the stack 37 which of course is built to the proper height for the purpose. This draft causes the products of combustion to circulate in the furnace chamber in the general direction of the duct 35, the rear end of the baffle wall 28 being rounded to promote circulation. The furnace is heated to the proper temperature upon which the cover 18 is removed and garbage and other waste matter introduced thru the opening 17. Owing to the forward curvature of the rear wall 12 at its intersection with the base 10, matter falling thereon has a tendency to work forwardly onto the grates 20 and 30.

The smoke and gases are drawn across the main combustion chamber and upward toward the draft opening 35. While an intense heat is had in the combustion chamber and the matter is incinerated therein, certain odoriferous gases will escape thru the duct 35. For this reason the auxiliary combustion chamber has been provided. This chamber being lined with fire brick or equivalent material becomes extremely hot and the gases passing thru the same are consumed or robbed of their obnoxious properties.

A certain portion of the garbage may be used for fuel and for this purpose the extension grate 25 is provided so that a portion of each deposit of garbage may be raked thereonto if desired. The grates 30 may be used for burning the garbage which may be raked onto the same and by opening the door 34 sufficient oxygen is admitted to promote combustion of the matter on said grates.

It is obvious that almost any condition encountered in the incineration of garbage and other waste matter may be handled to the best advantage in this furnace; and further it may be operated at a minimum expense owing to its economical fuel arrangements.

Various changes in the size and shape of the parts as well as alterations and modifications, may be made within the scope of the appended claims.

What I claim, is:

1. In an incinerator, a combustion chamber having an arch top provided with an opening for admitting garbage, a base at the bottom of the chamber, a fuel grate at one side of the main combustion chamber, a vertical baffle wall extending rearwardly

from the front wall of the main chamber and co-operating with the fuel grate and its adjacent wall to provide a fire fuel box, an extension fuel grate projecting beyond the baffle wall, an ash grate at the central front portion of the base, auxiliary garbage grates 65 at the side of the main chamber opposite to the fuel grates and contiguous to the ash grate, an auxiliary combustion chamber parallel to the main combustion chamber and having connection at one end only with the 70 main chamber, and a smoke stack having connection with the opposite end of the auxiliary chamber.

2. In an incinerator, a main combustion chamber having a baffle wall and grates, an auxiliary combustion chamber parallel to the main chamber, a duct connecting the two chambers at their front ends, and a smoke stack connected with the rear end of the auxiliary chamber.

3. In an incinerator, a main combustion chamber having a baffle wall and grates, an auxiliary combustion chamber parallel to the main chamber, a duct connecting the two chambers at their front ends, a smoke stack at the rear end of the auxiliary chamber, and a duct connecting the rear end of the auxiliary chamber with the stack, said duct being less in width than the auxiliary chamber, whereby the products of combustion 90 are retarded in said auxiliary chamber.

4. In an incinerator, a burning chamber having a baffle wall and grates, an auxiliary combustion chamber parallel to the burning chamber, an opening connecting the front 95 ends of the chambers, and a flue entrance at the rear end of the combustion chamber.

5. In an incinerator, a burning chamber having a baffle wall and grates, an auxiliary combustion chamber parallel to the burning chamber, an opening connecting the front 100 ends of the chambers, and a restricted flue entrance at the rear end of the combustion chamber.

6. In an incinerator, a burning chamber having a baffle wall and grates, an auxiliary combustion chamber parallel to the burning chamber, an opening connecting the front 105 ends of the two chambers, a smoke stack at the rear of the combustion chamber, and an 110 entrance between the rear end of the combustion chamber and the stack, said entrance being less in width than the combustion chamber, whereby the gases are retarded in said chamber.

In testimony whereof I affix my signature.

JOHN W. STOKES.
